FISHING LURE

George Paul Ritts and Lillian May Ritts, East Lansing, Mich.

Application August 16, 1957, Serial No. 47,408

Term of patent 14 years

(Cl. D31—4)

We claim:

The ornamental design for a fishing lure, as shown.
